F. RUSTANT.

NON-REFILLABLE BOTTLE,

APPLICATION FILED MAR. 16, 1920.

1,358,398.

Patented Nov. 9, 1920.

UNITED STATES PATENT OFFICE.

FERDINAND RUSTANT, OF SAN FRANCISCO, CALIFORNIA.

NON-REFILLABLE BOTTLE.

1,358,398.

Specification of Letters Patent.

Patented Nov. 9, 1920.

Application filed March 16, 1920. Serial No. 366,295.

To all whom it may concern:

Be it known that I, FERDINAND RUSTANT, a citizen of the United States, residing at San Francisco, in the county of San Francisco and State of California, have invented 5 certain new and useful Improvements in Non-Refillable Bottles, of which the following is a specification, reference being had therein to the accompanying drawings.

10 This invention relates to nonrefillable bottles, and has for its object the improvement of the construction of a bottle that will efficiently prevent the fraudulent refilling of the bottle but will permit the bottle to be emptied of its contents after it has been right- 15 fully filled.

Another object of the invention is the improvement of the construction of valve devices mounted in the neck of a bottle, which 20 valve devices coöperate for the prevention of fraudulent filling of the bottle but permit the bottle to be emptied of its original contents.

With these and other objects in view, my 25 invention comprises certain novel constructions, combinations, and arrangements of parts as will be hereinafter specifically described, illustrated in the accompanying drawings, and more particularly pointed out 30 in the appended claims.

In the drawings,

Figure 1 is a vertical sectional view of a bottle neck constructed in accordance with the present invention, showing the valve devices therein, while—

Fig. 2 is a sectional view taken on line 2—2, Fig. 1, looking in the direction of the arrows.

Fig. 3 is a sectional view taken on line 40 3—3, Fig. 1, looking in the direction of the arrows.

Fig. 4 is a sectional view taken on line 4—4, Fig. 2, looking in the direction of the arrows.

45 Fig. 5 is an enlarged, fragmentary, sectional view of the auxiliary valve device, while

Fig. 6 is a perspective view of the auxiliary valve device.

50 Fig. 7 is a view in side elevation of the primary sphere or ball.

Fig. 8 is a perspective view of the sliding weight.

Referring to the drawings by numerals, 1 55 designates the body of the receptacle or bot-

tle and 2 the neck thereof. In the neck is formed the primary portion 3 of the liquid canal or passage, and communicating with the passage 3 is an enlarged, right-angularly-extending passage portion 4, which passage 60 portion 4 communicates with a substantially U-shaped passage portion 5, the outer part of the U-shaped portion 5 turning inwardly at 6 (Fig. 1) and communicating with the central discharge portion 7. The portions 3, 4, 65 5, 6, and 7 constitute a peculiarly-shaped liquid passage, and I use the term liquid passage in the appended claims to designate the canal or passage whereby the liquid may be discharged from the body 1.

70 In the bottle neck 2, I form a comparatively large pocket 8 at the inner end of the passage portion 3, or the end of said passage portion 3 that might be termed the "top" with respect to the normal position of the 75 bottle. Communicating with this pocket 8 is a series of auxiliary sphere or ball-receiving sockets 9, preferably four in number, and at the central portion of pocket 8 is a depending extension 10 which acts to direct the 80 auxiliary spheres or balls 11 to their seated positions within the sockets 9, as shown in Figs. 1 and 2.

The primary crystal sphere or ball 12 is larger than the auxiliary balls 11, and this 85 ball 12 is free to travel a slight distance in the upper part of the passage portion 3. At opposite sides of the passage portion 3 are weight-engaged slots 13, which slots 13 receive the ends 14 of the sliding weight 15. 90 The weight has an extension 16, flat upon its outer face, which engages the "bottom" of the primary ball 12, to force the ball quickly "upward" or outward, when it is desired to pour liquid from the bottle, which weight 95 causes the ball 12 to positively move to the dotted position shown in Fig. 1, thereby permitting liquid to pass from the passage portion 3 into the passage portion 4 and thence through the other portions of the 100 liquid passage to the outer atmosphere.

The weighted or auxiliary balls 11 will act upon the primary ball 12 to force it down to its seated position as shown in Fig. 1, as soon as the bottle is slightly tilted in 105 either direction; it will be understood that all of the balls 11 are not acting on the ball 12 at the same time, but by reason of nesting several balls 11 around the primary ball (see Fig. 3), at least one is ready to strike and 110

engage and bear upon the ball 12 as soon as the bottle is slightly tilted from a vertical position.

The sliding weight 15, the primary ball 12, and the auxiliary balls 11, together with the peculiar construction of the pocket 8, central depending portion 10, and the sockets 9, constitute a primary valve device in my non-refillable bottle, and now I will 10 proceed to specifically describe the auxiliary valve device:

The auxiliary valve device comprises an elongated pocket 17 substantially parallel with the passage portion 3, and in this 15 pocket 17 is slidably mounted the valve frame 18, which frame 18 is provided with an outlet opening 19, and on the inner end of the opening 19 a shoulder 20 (Fig. 5) is formed, and within the lower end of 20 opening 19, at 21, is hingedly or pivotally mounted the flap valve or gate 22, which valve 22 will close the opening 19 when liquid is fraudulently being attempted to be passed through the liquid passage into the 25 body of the bottle. The valve 22 will readily open when the contents of the bottle are being discharged through the passage, but when an attempt is made to fraudulently fill the bottle usually by inverting the bottle, 30 then the valve frame slides down and the upper end 18 enters the socket 23 (Fig. 1). If the bottle is retained in its vertical position (Fig. 1), and liquid is endeavored to be fraudulently forced into the body through 35 the passage, then the primary valve 12 will prevent this by remaining seated in the passage portion 3, closing the entire passage, as shown, the auxiliary weighted balls 11 causing the primary ball to move to its 40 closed position, as hereinbefore specifically pointed out.

It is to be understood that the spheres or balls may be formed of different material, and suitably covered or coated to prevent the liquid contained in the bottle from 45 injuring the same or corroding, and the parts of the auxiliary valve device can be formed of suitable material to make same positive in operation. Therefore, I reserve 50 the right to make such alterations and changes in the manufacture or construction of my nonrefillable bottle as will appear to one skilled in the art to which this invention relates, which alterations or changes 55 shall fairly fall within the scope of the appended claims.

What I claim is:

1. In a nonrefillable bottle, the combina-

tion of a neck provided with a liquid passage, a ball normally seated in said passage for closing the same against liquid flowing in one direction therethrough, said neck provided with oppositely-positioned slots opening into said passage, a sliding weight having its ends seated in said slots 60 provided with a flat extension adapted to engage said ball for moving the ball to an open position, and means carried by the neck and freely movable in the passage for engaging the ball for returning the same to 65 its normal seated position, after the ball has been moved to its normal open position by said sliding weight.

2. In a nonrefillable bottle, the combination of a bottle neck provided with a liquid 70 passage, said neck provided with an elongated pocket and a socket in alignment with the pocket, a sliding valve frame in the pocket adapted to have its outer end rest in the socket, said valve frame provided 75 with an opening and a shouldered portion formed in the frame at one side of the opening, a valve hingedly mounted in the frame at the opposite side of the opening and the valve adapted to have one edge 80 seated in the shouldered portion, and primary valve means in the liquid passage for 85 normally closing the same.

3. In a nonrefillable bottle, the combination of a neck provided with a liquid 90 passage, a primary valve device in said passage and including a primary ball and a plurality of auxiliary balls, and an auxiliary valve device working in said passage and including a sliding frame provided with a 95 valve, the valve to open within the passage for allowing liquid to flow out through the bottle neck, but the valve to close to prevent fraudulent filling of the bottle.

4. In a nonrefillable bottle, the combination of a neck provided with a liquid passage, said neck provided with means for normally holding a plurality of balls in a nested position around a portion of the liquid passage, valve means movably mounted in and normally closing said passage, any one of said balls adapted to engage said valve means for returning the same to its normal seated position, and auxiliary valve means working in said passage and being 100 adapted to prevent the fraudulent refilling 105 of the bottle.

In testimony whereof I hereunto affix my signature.

FERDINAND RUSTANT.
